LOCKSMITH'S TRAY FOR HOLDING LOCK PARTS

William E. Zipf, Franklin County, Ohio, assignor to
Zipf Lock Company, Columbus, Ohio

Filed Sept. 30, 1970, Ser. No. 25,273

Term of patent 14 years

Int. Cl. D3—99

U.S. Cl. D87—1

FIG. 1

FIG. 2

FIG. 3

FIG. 4

FIG. 1 is a perspective view of a locksmith's tray for holding lock parts showing my new design;

FIG. 2 is a medial longitudinal vertical sectional view taken along a plane indicated by the line 2—2 of FIG. 1;

FIG. 3 is a side elevational view looking toward the side of the tray opposite that shown in FIG. 1; and

FIG. 4 is an end elevational view looking toward the end of the tray opposite that shown in FIG. 1.

I claim:

The ornamental design for a locksmith's tray for holding lock parts, substantially as shown.
